DESIGN FOR A CARROUSEL

Lowell M. Glasco, Dallas, Tex.

Application November 19, 1945, Serial No. 123,873

Term of patent 14 years

(Cl. D34—5)

To all whom it may concern:

Be it known that I, Lowell M. Glasco, a citizen of the United States, residing at Dallas, in the county of Dallas and State of Texas, have invented a new, original, and ornamental Design for a Carrousel, of which the following is a specification, reference being had to the accompanying drawing, forming part thereof.

Figure 1 is a top perspective view of my new design for a carrousel.

Figure 2 is a plan view, and

Figure 3 is a side elevational view.

I claim:

The ornamental design for a carrousel, as shown.

LOWELL M. GLASCO.
